SOAP DISPENSER

Robert V. Burt and Robert J. Short, Cincinnati,
Ohio, assignors to The Procter & Gamble Com-
pany, Cincinnati, Ohio, a corporation of Ohio

Application January 23, 1933, Serial No. 652,980

4 Claims. (Cl. 221—102)

Our invention relates to soap dispensing apparatus, particularly for dispensing soap paste and cream soap.

It is the object of our invention to provide a soap dispenser in which a cartridge of soap in paste form may be inserted in the dispenser, and in which mechanism is provided to facilitate the dispensing of substantially measured quantities of the product from the dispenser.

Another object of our invention is the provision of dispensing equipment in which means is provided for registering automatically the quantity of soap retained in the supply part of the dispenser so that when it becomes empty it may be properly serviced without the annoyance to people using the dispenser of having them attempt to cause the discharge of a quantity of the soap for use when the supply is exhausted.

Another object of our invention is the provision of a valve which tends to prevent the drip from the dispensing orifice at the end of a dispensing operation.

Another object of our invention is the provision of a dispenser which may be formed from die casting or moulded plastic resinoid, or the like, which will have a neat and attractive appearance, and which will be sturdy and not likely to get out of order with continuous operation.

The above objects and other objects to which reference will be made in the ensuing description we accomplish by that certain combination and arrangement of parts of which we have shown a preferred embodiment.

Referring to the drawings:

Figure 1 is a vertical sectional view of the dispenser.

Figure 2 is a side elevation of the dispenser taken at an angle of 90 degrees from the sectional view shown in Fig. 1.

Figure 3 is a detail sectional view of the discharge nozzle.

The dispenser has a bracket shaped base 1, having a vertical flanged portion 2, which openings 3 are formed to attach the base to a vertical support as with screws or bolts.

The base has a cup shaped depression 4 and a number of pins 7 extend from the base within the depression. Bayonet slots 5 are formed close to the end of a cover portion 6 of the dispenser so that the cover may be locked in position by a slight rotation on the base.

The cover has a cap portion 8, through which a passage 9 extends, and a dial cap 10 having an arrow 11 thereon seats against the flat top 12 55 of the cap 8.

The base has a circular orifice 13 therein which seats the end 14 of the shaft 19.

A gravity platen 16 is secured to the base of the hub 15 which has a hole 17 shaped to fit the shaft 19 which is preferably formed from a 60 twisted rectangular bar. The platen 16 is prevented from slipping off the shaft 19 by a pin 18 extending through the end of the shaft 19. The shaft 19 extends up through the opening 9 in the cap and is secured to the dial 10. A rod 20 65 extends down from the cap 8, passing through an orifice 22 in the platen 16, and because of the axial mounting and the guide 20, the platen 16 is prevented from rotating when it follows down on top of the soap as it is dispensed. The purpose of the gravity platen is to maintain a uniform level of the soap as it is drawn into the chamber 28, thus preventing soap from being drawn preferentially from one section of the dispenser and permitting air from entering the 75 chamber before the soap is completely discharged from the container.

Since the platen 16 is held immovable as to rotation as it descends, it causes the shaft 19 to rotate so that the arrow 11 will move through 80 an angle of 180 degrees from a portion of the cap 8 of the dispenser provided with the indicia 23, indicating that the container is full, to indicia 24, indicating that the container is empty.

The soap in paste form is provided in a package having an outer shell 25, preferably made of cardboard and having a diameter of such size as to clear the outer peripheral edges of the platen 16 so that it will be free to move down within the wall of the package.

A recess 26 seats the lower edge of the wall 25, and the cover is then placed in position with the studs 7 interlocking in the bayonet slots 5 of the cover 6. The rod 20 passes down through the soap, and the lower end 14 of the axial shaft 19 95 engages within the recess 13. The platen with the hub 15 remains on top of the soap and as the soap is dispensed its descent within the container causes the rotation of the twisted shaft 19 and of the dial 10.

The base 1 is provided with a chamber 27, into which the soap paste flows by gravity and the pressure of the platen 16. A passage 28 extends laterally across through the base 1, and this passage has a branch passage 29 which extends 105 down to the dispensing portion 30 of the base.

Within the passage 28 there is a valve casing 29^a which seats a ball 30^a. The ball is retained within the valve casing 29^a by means of a split ring 31.

90

95

100

105

110

The casing, 29^a, the ball 30^a, and the split ring 31 provide a valve which prevents soap from passing back from the chamber 28, through the seat 32 of the valve casing.

5 A plunger 33 is mounted for lateral reciprocating motion in the chamber 28. The plunger has a collar 34, against which a coil spring 35 bears, tending to move the piston to the right, as indicated in Fig. 1. Secured to the piston 33 is a rod 10 36, having a push handle 37.

When the push handle is pressed inwardly it causes the semisolid soap to move the ball 30^a against the seat 32 and thus causes the soap from the chamber 28 to be discharged down the 15 passage 29 to the dispensing orifice 30, moving spring 41 outwardly, and thus discharging the soap. Spring 41 is provided with a small opening 38 at the bottom as shown in Figure 3, so that when the said spring is seated, passage 29 20 is not entirely closed. The opening 38 is of such size and shape as to prevent the soap paste from flowing outwardly by gravity but will permit soap to be drawn inwardly by the suction of the plunger 33.

25 At the discharge orifice the front of the base is shaped out and a plate 39 is secured to the machine surface as by means of a screw 40. A plate of spring steel 41 is secured between the discharging portion of the base and the plate 39, being held in position by means of a stud 42 and a properly shaped depression in the plate 39.

The plunger 33 is retained within the base by means of a stuffing box cap member 43. Plug 44 35 is provided to facilitate the drilling out of the chamber in the base and for rendering the dispenser easy to clean out. Set screw 45 is provided for the purpose of holding the ball check valve casing 29^a in place.

40 Each inward pressure stroke of the plunger empties the passage 28, and upon the release of the push handle 37, the plunger is forced back by the spring 35, thus drawing a new charge of soap through the ball valve into chamber 28, 45 and at the same time drawing in any soap which may remain hanging to the outside of orifice 30.

The method of using the dispenser is to seat within the recess in the base an open ended container of soap paste. The platen 16 is then 50 placed on top of the soap, its peripheral dimensions being such that it slides down within the walls of the container. The cover is then inserted on the base with the bayonet lugs locking within the bayonet slots. During the positioning of 55 the cover the stub end 14 of the shaft 19 seats within the recess 13. The guiding of the platen 16, preventing its rotary movement, causes the shaft 19 to rotate, and the arrow 11 indicates the level of the soap paste within its container.

60 It should be understood that the drawings and description shown herein embody one form of our invention, but that certain modifications in

details may be made. For example, the casing and the soap container may be made of other shapes, such as rectangular, instead of round, and the guiding rod 20 thereby made unnecessary; and other minor changes in construction are possible without departing from the spirit of our invention.

Having thus described our invention, what we claim as new and desire to secure by Letters Patent, is:—

1. In a soap dispensing device, a base, a cover member detachably mounted on the base and projecting upwardly therefrom so as to supply a container portion, a tube containing soap paste located within said container portion, a follower located in the cover member and arranged to lie within the tube and rest on the soap paste therein when said tube is inserted into the cover, and having a guide member extending through the said soap paste, and a contents gauge arranged to be operated by said follower located outside of the cover member.

2. In a soap paste dispenser, the combination of a compressor chamber and piston therein, a valve admitting soap to said compressor but 100 checking its outflow therefrom, a dispensing conduit, and a valve for said dispensing conduit located at the discharge orifice thereof, said valve so constructed as to incompletely close the discharge orifice during the suction movement of 105 the piston permitting drawing in of extruded paste, and to open the discharge orifice during the compression movement of the piston.

3. In a soap paste dispenser, the combination of a compressor chamber and piston therein, a 110 valve admitting soap to said compressor but checking its outflow therefrom, a dispensing conduit, and a valve for said dispensing conduit located at the discharge orifice thereof, said valve so constructed as to incompletely close the discharge orifice during the suction movement of 115 the piston permitting drawing in of extruded paste, and to open the discharge orifice during the compression movement of the piston, said valve being in the form of a plate having a small 120 opening therein insufficient to permit leakage of the paste in the absence of pressure.

4. In a soap paste dispenser, the combination of a compressor chamber and piston therein, a valve admitting soap to said compressor but 125 checking its outflow therefrom, a dispensing conduit, and a valve for said dispensing conduit located at the discharge orifice thereof, said valve so constructed as to incompletely close the discharge orifice during the suction movement of 130 the piston permitting drawing in of extruded paste, and to open the discharge orifice during the compression movement of the piston, said valve when closed being sufficient to prevent leakage of paste in the absence of pressure.

135 ROBERT J. SHORT.
